Primary Examiner — Michelle E. Wilson*Assistant Examiner* — Clese Moore, Jr.(74) *Attorney, Agent, or Firm* — Ross Brandborg(57) **CLAIM**

I claim the ornamental design for a baby blanket, as shown and described.

DESCRIPTION

FIG. 1 is a front perspective view of a baby blanket, shown with the bottom skirt detached;

FIG. 2 shows an front view thereof;

FIG. 3 shows a back view thereof;

FIG. 4 shows a left-hand side view thereof;

FIG. 5 shows a right-hand side view thereof;

FIG. 6 shows a close up of the snaps where the bottom skirt attaches with the top snap band rolled up for visualization. FIG. 7 shows a close up of the snaps where the bottom skirt attaches with the top snap band down.

FIG. 8 shows a front perspective view of the invention with the bottom skirt attached;

FIG. 9 shows a front view thereof;

FIG. 10 shows a back view thereof;

FIG. 11 shows a left-handed side view thereof; and, FIG. 12 shows a right-handed side view thereof.

Certain lines and dots are presented herein to provide shading in order to provide a fuller understanding of the invention. Such shading lines and dots form no part of the claimed design. Certain singular broken lines are present to show the environment and form no part of the claimed invention
